(57) **CLAIM**

The ornamental design for a toy gun, as shown and described.

DESCRIPTION

FIG. 1 is a front, right and top perspective view of a toy gun, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof; and,

FIG. 9 is an enlarged view of area “9” in FIG. 1.

The evenly broken lines shown in the drawings depict portions of the toy gun that form no part of the claimed design. Additionally, the dot-dash broken lines around the enlargement indicia in FIGS. 2 and 9 are shown for the purpose of illustrating the bounds of the enlargements and form no part of the claimed design.
